UNITED STATES PATENT OFFICE.

LEWIS NORBERT BENSON, OF WENATCHEE, WASHINGTON.

ELEVATING CONVEYER.

Application filed September 29, 1924. Serial No. 740,632.

This invention relates to elevating conveyers and is designed more particularly for raising boxes of fruit from the lower floor of a warehouse to an upper floor of the same although it may, of course, be employed in other fields. The primary object of the invention is to provide a structure in which the boxes or other objects being raised will be held against tilting during their upward movement and also will be held in a level position while passing around the upper bight of the elevating chain. Another object of the invention is to provide means for the stated purpose which will be simple and compact and easily operated.

The invention is illustrated in the accompanying drawings, in which—

Figure 1 is a front elevation of an elevator embodying my improvements;

Fig. 2 is a vertical section on the line 2—2 of Fig. 1;

Fig. 3 is an enlarged transverse section of the upper end of the elevator;

Fig. 4 is an enlarged view, partly in side elevation and partly in section, of the mechanism shown in Fig. 3, and

Fig. 5 is a horizontal section on the line 5—5 of Fig. 1.

The frame of the elevator may be of any desired or approved form which will possess the requisite strength and rigidity. It is illustrated in the accompanying drawings as consisting of posts or uprights 1 arranged in spaced rectangular relation and having guide rails 2 secured to their outer sides and extending the full length of the same. The posts or uprights are connected at intervals by cross beams of any preferred form whereby they are held in the proper relation, and these cross bars may be in turn connected by stay rods 3, as indicated most clearly in Figs. 3 and 4. Near the lower end of the elevator frame is provided a loading platform which is illustrated as consisting of rails 4 projecting forwardly from the frame and secured rigidly thereto and supporting rollers 5 upon which the box to be elevated may be placed and moved easily into position to be engaged by the platforms or lifting members of the elevator. The loading platform, however, need not be secured to the elevator frame but may be built as a part of the floor of the warehouse and may be dispensed with entirely if its use be deemed unnecessary or other means for plac-

ing the boxes or other objects in position to be engaged by the elevator be preferred.

Near the lower end of the elevator frame is journaled a shaft 6 and upon the said shaft adjacent the uprights 1 are secured 60 sprocket wheels 7 around which the elevating conveyer chains 8 are trained. Upon the upper ends of the uprights is mounted a shaft 9 which is similar to the shaft 6 and upon which are secured the sprocket wheels 65 10 arranged in the same vertical planes as the respective sprocket wheels 7 and about which the elevator chains are trained, as clearly shown. Vertical bracing bars 11 are preferably extended between the shafts 6 70 and 9 so as to impart additional rigidity to the frame and to support the shafts against bending under strain. Extending between the chains 8 and pivotally attached thereto at its ends is a rod 12 which constitutes the 75 base rod of the platform or carrier of the elevator. While the present drawings show only one of said rods, it will be understood, of course, that they may be provided at any desired intervals along the chains and the 80 number of rods or carriers will be dependent, to a great measure, upon the size of the building and the resultant number of floors which are to be served by the elevator. Near the ends of the carrier rod 12 guide rollers 85 13 are mounted thereon, and these rollers, as shown most clearly in Fig. 5, are arranged to ride upon the inner faces of the rails 2 which are provided at the front and back of the elevator frame so that the carrier will 90 be guided during its vertical movements. The rod 12 carries a shelf or support which may be of any convenient or approved form and is illustrated as consisting of two substantially T-shaped bars 14 having their 95 stems fitted to and depending below the rod and their heads disposed transversely to the rod and projecting equi-distantly in front and in rear of the same, as will be readily understood upon reference to Fig. 4. The 100 bars 14 are disposed in vertical planes and, of course, are parallel. The lower ends of the stems of the T-shaped bars are connected by a rod 15 which extends laterally beyond the said stems and is equipped at its 105 ends with rollers 16 adapted, like the rollers 13, to ride upon the inner faces of the guide rails 2. The engagement of these rolls with the guide rails 2 effectually maintains the 110 stems of the shelves in a vertical position 110

during the ascent or descent of the carrier and, therefore, an object, such as the box illustrated at 17, will be kept level during the raising of the same from a lower floor 5 to a higher floor, and it may be here stated that the elevator may be used to convey objects from an upper floor to a lower floor.

Secured rigidly to the cross rods 12 and 15 and preferably arranged near one side 10 of the elevator frame is a segmental rack 18 which, as shown clearly in Figs. 2 and 4, is concentric with the rod 12 and defines a semi-circle. Upon the shaft 9 at the upper end of the elevator frame and arranged in 15 the same vertical plane with the segmental gear 18 is a pinion 19 which is rigid with a sprocket pinion 20, the pinion and the said sprocket being loose upon the shaft and held against movement along the same by 20 stop collars 21 in an obvious manner.

A driving shaft 22 is mounted in the elevator frame below the shaft 9, and upon the countershaft is secured a sprocket pinion 23 about which and the sprocket 20 is trained a 25 chain 24. Upon one end of the shaft 22 is secured a pinion 30 which meshes with an internal gear 31 which is secured upon the end of the shaft 9. Of course, when motion is imparted to the gear 31, the shaft 9 will be 30 rotated and motion thereupon imparted directly to the elevator chains 8 so that the shelf or carrier will be caused to move upwardly or downwardly relative to the elevator frame. A band pulley 28 is secured 35 upon the shaft 22 and a belt 29 applies power thereto from any convenient motor.

The arms 14 which, in the present instance, are shown as constituting the shelf or carrier, are so spaced that they will pass 40 between the rails 4 of the loading platform and a box placed upon the said platform at the end of the same and partly projecting into the space between the front uprights of the elevator frame will be in the path of 45 said shelf or arms passing around the lower bight of the elevator and then rising, as will be readily understood. As the upward movement of the shelf continues, it will be brought against the bottom of the box 17 or other object and, of course, will lift the 50 same. The box is maintained in a level position during its ascent by the engagement of the rolls 13 and 16 with the track rails 2, and it is to be noted at this point that the 55 said rails have their upper ends disposed at the horizontal plane of the shaft 9. The segmental gear 18 has a radius equal to the radius of the driving sprocket 10 at the upper end of the elevator. As the shelf reaches 60 the upper end of the elevator frame, the inner corner or end of the segmental gear will

mesh with the spur pinion 19 and, as this pinion is being rotated idly upon the shaft 9 through the medium of the chain 24 and the sprocket 20, it will tend to swing the 65 segmental gear about the rod 12 as a center. Inasmuch, however, as the shelf to which the supplemental gear is attached is traveling upwardly and will necessarily follow the path defined by the chains 8 to which the 70 rod 12 is attached, the result of the engagement of the pinion 19 with the segment 18 will be to maintain the shelf in a level position during the entire period of its travel up over and then down around the shaft 9. 75 Premature discharge of the box or spilling of its contents is thus avoided and the handling of the box is facilitated. By referring to Fig. 4, it will be readily noted that the segmental gear will be in mesh with the 80 pinion 19 during one-half of a revolution of the sprocket 10 so that the pinion will enter into engagement with the segment at one corner or end of the same and will leave the segment at the opposite corner thereof. 85 The arrangement is especially desirable in those instances where the box or other object is received by the elevator at one side of the same and removed therefrom at the opposite side thereof, as where it is arranged 90 and practically used to convey articles from an outside platform to an upper floor of a building.

My apparatus is exceedingly simple in the construction and arrangement of its parts 95 and will operate efficiently at all times to maintain the object or box in a level position.

Having thus described the invention, I claim:

In an elevator, the combination of an elevator frame, guide rails thereon, a shaft mounted at the upper end of the elevator frame, sprockets on said shaft, elevator chains trained around said sprockets, a rod disposed between and connected with said chains, a shelf secured on said rod, a second rod carried by the shelf below the first rod, rollers upon both said rods adapted to engage the guide rails on the elevator frame, a pinion loose on the said shaft, a pendant segmental gear secured to the said rods and disposed in the same vertical plane as the said pinion, a driving shaft mounted in the frame below the first-mentioned shaft, a pinion on one end of said shaft, an internal gear on the end of the first-mentioned shaft meshing with said pinion, and sprocket gearing connecting the drive shaft with the pinion on the first-mentioned shaft.

In testimony whereof I affix my signature.
LEWIS NORBERT BENSON.
